DESIGN FOR A RUG

William F. McCabe, New York, N. Y., assignor to Bigelow Sanford Carpet Co., Inc., a Corporation of Massachusetts

Application May 1, 1933. Serial No. 47,963

Term of patent 7 years

To all whom it may concern:

Be it known that I, WILLIAM F. McCABE, a citizen of the United States, residing at New York, in the county of New York and State of New York, have invented a new, original, and ornamental Design for a Rug, of which the following is a specification, reference being had to the accompanying drawing, forming part thereof. The drawing illustrates a portion of a carpet showing my design.

I claim:

The ornamental design for a rug substantially as shown.

WILLIAM F. McCABE.
